UNITED STATES PATENT OFFICE.

WALTER S. ROCKWELL, OF NEW YORK, N. Y.

FORGE.

SPECIFICATION forming part of Letters Patent No. 687,389, dated November 26, 1901.

Application filed May 21, 1900. Serial No. 17,425. (No model.)

To all whom it may concern:

Be it known that I, WALTER S. ROCKWELL, a resident of New York, in the county of New York and State of New York, have invented 5 certain new and useful Improvements in Forges; and I do hereby declare the following to be a full, clear, and exact description of the invention, such as will enable others skilled in the art to which it appertains to make and 10 use the same.

My invention relates to an improved forge, the object of the invention being to provide an improved portable forge operated by atomized liquid fuel and which will be extremely 15 simple in construction, comparatively cheap to manufacture, and most effectual when in use.

With this object in view the invention consists in certain novel features of construction and combinations and arrangements of parts, as will be more fully hereinafter described, and pointed out in the claims.

In the accompanying drawings, Figures 1 and 2 are views in vertical section, taken at 25 right angles to each other; and Fig. 3 is a view in horizontal section on the line $x-x$ of Fig. 1.

A represents a cylindrical tank or reservoir for hydrocarbon, the side walls of which 30 project above the top 1 thereof and the base of said tank provided with an angle-iron or flanged ring 2, as shown.

My improved forge B is provided on its bottom with a circular flange 2^a, disposed in 35 the upper end of the upwardly-projecting walls of the tank A, the top of said forge being arched and provided with eyebolts 3 to facilitate removing the same from the tank when desired. A pipe-coupling 4 is secured 40 in the upper end of tank A and comprises a casing divided by a diagonal partition 5 into two chambers 6 and 7, which latter chamber communicates with the interior of the tank. An air-inlet pipe 8 communicates with the

45 chamber 7, and a vertical pipe 8^a, of smaller diameter than the chamber 7, is disposed therein, passes through the partition 5, and communicates with the chamber 6, and said pipe 8^a extends down into the tank A and 50 terminates near the bottom thereof, where it is provided with any approved strainer 10.

An oil-outlet pipe 9 communicates with the

chamber 6, and said pipes 8 and 9 are bent at right angles and extend parallel outward, and short pipes 13 connect the outer ends of 55 said pipes 8 and 9 with a common outlet spout or atomizer 14, having a valve 16 to regulate the flow therethrough. The pipes 13 are provided with valves 11 and 12, respectively, to regulate the passage there- 60 through to the atomizer or spout 14, which is also adapted to serve as a burner to direct the flame into the forge B through an opening 17 in one end thereof, and said forge is provided with an inner coating of fire-clay 18 65 and with a transverse bridge-wall 19 near its forward open end, over which the flame is compelled to pass to distribute the heat throughout the entire interior of the forge, and an inlet-opening 20 for rivets or other 70 articles to be heated is provided in the side wall of the forge just back of the bridge-wall, which opening also serves as an outlet for the burned gases and other products of combustion. 75

An air-inlet pipe 21 extends transversely beneath the forge and is adapted at one end for the attachment of any approved air-supply and is connected between its ends to the pipe 8 by a pipe 22, which latter is provided 80 between its ends with any approved air-regulator C to regulate the pressure of air passing therethrough. The other end of pipe 21 is bent upward and communicates with a horizontally-disposed perforated pipe 23, 85 mounted in a plane just below the opening 20 in the side wall of the forge, so as to deflect the burned gases and other products of combustion escaping through said opening up behind a screen or shield 24, secured to 90 the forge by arms 24^a, and hence protect the operator from the injurious effects of such gases and products of combustion. The pipe 21 is provided near pipe 23 with a suitable valve 25 to regulate the pressure of air fed to 95 said pipe 23.

An oil-inlet pipe 26 communicates with pipe 9, is normally closed by a cap 27, and is provided between its ends with a check-valve 28 to prevent oil from escaping therethrough. 100

Suitable handles 29 are provided on the tank or reservoir A to facilitate moving the same, and a petcock 30 is provided in tank A, near the top thereof, to permit the air to

escape when the tank is being filled, and which also serves as an overflow to indicate when the tank is filled sufficiently. At all points where the pipes pass through the walls 5 of the tank they are secured against movement by jam-nuts, as shown.

The operation of my improvements is as follows: When it is desired to fill the tank, it is simply necessary to attach an oil-supply 10 pipe to oil-inlet pipe 26 and pump or otherwise force the oil therein, which will flow past check-valve 28 into pipe 8 and from thence down through pipe 8^a into tank A, the petcock 30 being previously opened to permit the air in the tank to escape, and as soon as a sufficient amount of oil is in the tank the petcock will be closed and the oil-supply pipe removed and cap 27 secured onto the inlet-pipe 26 to protect the same. 15

20 In operation air is forced into pipe 21 and through the air-regulator C into pipe 8, where it flows in both directions, as indicated by the arrows, one part of the volume of air passing to the valve 11 and the other part of 25 the air passing through the chamber 7 into the upper portion of the tank or reservoir A to force oil up through pipe 8^a into chamber 6 and through pipe 9 to the valve 12, when both valves 11 and 12 can be opened, and the 30 air and oil will commingle in spout 14 and be ejected therefrom and ignited and the flame blown through the opening 17 into the forge and against the bridge-wall and the heat deflected to all parts of the forge, and the products of combustion will escape through the 35 opening 20, and the air-blast which escapes through perforated pipe 23 will force the products of combustion up behind the screen 24 and protect the operator from the evil effects thereof while inserting or withdrawing 40 articles from the forge.

Various slight changes might be resorted

to in the general form and arrangement of the several parts described without departing from the spirit and scope of my invention, 45 and hence I would have it understood that I do not wish to limit myself to the precise details set forth, but consider myself at liberty to make such slight changes and alterations as fairly fall within the spirit and scope of 50 my invention as claimed.

Having fully described my invention, what I claim as new, and desire to secure by Letters Patent, is—

1. In a forging apparatus, the combination 55 with a hydrocarbon-tank and a casing or furnace supported thereby and having two openings, of a burner communicating with the oil-tank and arranged to project a flame through one of said openings in the casing or furnace, 60 an air-pipe arranged to discharge air in front of the other opening in the furnace to deflect products of combustion emitted therefrom and means common to said air-discharge pipe and burner for supplying air to both. 65

2. In a forge, the combination with a casing lined with fire-clay and having an opening in its side wall for the admission of articles to be heated and an opening in its end for the admission of flame, of a bridge-wall 70 disposed in said casing between said openings, a screen secured to said casing and spaced therefrom in proximity to the opening in the side of the casing and an air-discharge disposed beneath said last-mentioned opening 75 and adapted to force the products of combustion behind the screen.

In testimony whereof I have signed this specification in the presence of two subscribing witnesses.

WALTER S. ROCKWELL.
